UNITED STATES PATENT OFFICE.

BURT E. TAYLOR, OF MOUNT VERNON, NEW YORK, ASSIGNOR TO THE BORDEN COMPANY, OF NEW YORK, N. Y., A CORPORATION OF NEW JERSEY.

CLOSURE FOR JARS AND THE LIKE.

Application filed January 24, 1924. Serial No. 688,142.

To all whom it may concern:

Be it known that I, BURT E. TAYLOR, a citizen of the United States, residing in Mount Vernon, in the county of Westchester, 5 in the State of New York, have invented certain new and useful Improvements in Closures for Jars and the like, of which the following is a specification.

The invention relates to an improvement 10 in closures for jars and the like adapted to contain and preserve in vacuum, fruits, vegetables, other articles of food and the like.

When fruits, vegetables and other articles 15 of food are preserved in receptacles, such as glass jars and tin cans, the receptacles are vacuumized before they are sealed. Considerable difficulty has been experienced in breaking the vacuum in the receptacles so as to remove the cover to get at the contents 20 and many efforts have been made to provide jar and can closures of such construction as to overcome this difficulty. The object of the present invention is to produce an improved simplified jar or can closure having 25 provision whereby the contents of the jar or can are kept hermetically sealed and having provision whereby the vacuum may be readily broken and the cover easily removed. To this end the invention consists in the 30 improved closure for jars and the like more fully described hereinafter and particularly pointed out in the appended claims.

The preferred form of the invention is 35 illustrated in the accompanying drawings in which Fig. 1 is a longitudinal section through the upper part of a glass jar showing the improved closure applied thereto; Fig. 2 is a plan of the parts shown in Fig. 1 with a portion of the outer cover broken away; Fig. 3 is a longitudinal section through the inner cover, showing the lining and cap separated therefrom; Fig. 4 is an enlarged section through the central part of the inner cover showing the cap in place over the 40 vent; and Fig. 5 is a fragmentary section, on an enlarged scale, showing the arrangement of the closure parts with relation to the neck of the jar.

The jar or can to which the improved closure is applied may be of any preferred 50 shape and size. In the illustrated embodiment of the invention the improved closure is shown applied to a cylindrical glass jar 7 having its upper end contracted to form a 55 neck 8 which is provided internally with a

seat or shelf 9. On the shelf 9 is adapted to be seated a disc or plate 10 which serves as an inner cover. The plate 10 substantially fills the space provided by the shelf 9 and is protected from contact with the contents of the jar by means of a paper or fibre washer or lining 11 which covers the bottom of the plate and is interposed between the rim of the plate and the shelf 9. Around the rim of the plate 10 is a raised rib or ring 12 which, 60 when the plate and lining are in place in the neck of the jar, projects upwardly slightly beyond the top edge of the jar, so that when the cup-like, threaded outer cover 13 is screwed down onto the upper end of the jar, 65 as shown in Fig. 1, the under-surface of the cover will engage the top of the rib 12, thereby forcing the plate 10 and the lining 11 tightly against the seat or shelf 9. The raised rib or ring 12 may be formed in any 70 preferred way and is conveniently made by pressing up the rim of the plate 10 at this point, as shown in Fig. 5. The rib 12 and the adjacent part 14 of the neck of the jar provide between them an annular space 15 75 adapted to receive a sealing substance 16, such as melted paraffin or gum, to seal the joint between the rim of the plate and the neck of the jar.

In the center of the plate 10 and the lining 11 is a vent or vacuum hole 17 which is closed by a cap 18 in the form of a flat, relatively small disc or plate. In order that the joint between the cap 18 and the plate 10 may be hermetically sealed to preserve the 90 vacuum in the jar, the plate 10 is provided with the raised portion or ring 19 surrounding the vent 17 and within which the cap 18 is placed. The ring 19 serves to provide a recess for the sealing substance which seals 95 the joint between the cap 18 and the adjacent part of the plate 10 around the vent.

When the jar has been filled with the fruit, vegetables or other product to be preserved and the contents of the jar have been 100 subjected to the requisite preliminary treatment, the lining 11 and plate 10 are first placed in position in the mouth of the jar and then the annular space 15 is filled with melted paraffin or gum. The cap 18 is then 105 placed over the vent 17 and the jar is introduced into the vacuum chamber, in the usual manner, and subjected to the proper degree of vacuum. The loose connection between the cap 18 and the plate 10 permits the in- 110

side of the jar to be properly vacuumized. While the jar is in the vacuum chamber melted wax or gum is poured over the top of the cap 18 and the joint between it and the plate 10 is thereby sealed. When this wax or gum is sufficiently hardened the jar is removed from the vacuum chamber and the cover 13 is screwed down onto the upper end of the jar, thereby completely enclosing and protecting the inner cover and at the same time forcing it against its seat. To open the can it is simply necessary to unscrew the cover 13, pry up the cap 18 with a sharp-pointed instrument, thereby permitting air to enter the jar through the vent 17, after which the inner cover or plate 10 and lining 11 are easily lifted from their seat.

Having thus described the invention what I claim as new is:—

- 20 1. A closure for jars and the like comprising a disc seated within the neck of the jar and having a vent, the rim of the disc having a raised portion forming with the adjacent part of the neck of the jar a groove adapted to receive a sealing substance, a cap adapted to rest on the disc to seal the vent, and an outer cover threaded onto the neck of the jar and bearing against the raised portion of the disc.
- 25 2. A closure for jars and the like comprising, a plate adapted to be seated within the neck of the jar and having a vent, a raised rib extending around the rim of the plate and forming with the adjacent part of the neck of the jar an annular space to receive a sealing substance, a cap for closing the vent in the plate, and a cover fitted onto the neck of the jar and bearing against the rib, thereby forcing the plate against its seat.

3. A closure for jars and the like comprising, a plate adapted to be seated in the neck of the jar and having a vent surrounded by a ring rising from the plate, an annular rib on the rim of the plate and providing with the adjacent part of the neck of the jar an annular space to receive a sealing substance, a cap for closing the vent, the raised portion about the vent providing a recess to receive a sealing substance to seal the joint between the cap and the plate, and a cover enclosing the upper end of the jar.

4. A closure for jars and the like comprising, a plate adapted to be seated in the neck of the jar and having a vent, a raised rib around the rim of the plate forming with the adjacent part of the neck of the jar an annular space to receive a sealing substance to seal the joint between the plate and the jar, a cap for closing the vent, a raised portion on the plate surrounding the cap and adapted to receive a sealing substance to seal the joint between the cap and the plate, and a cover enclosing the upper end of the jar and bearing against the rib on the plate.

5. A closure for jars and the like comprising, a plate adapted to be seated in the neck of the jar and having a vent, a lining on the underside of the plate, a ring rising from near the edge of the plate and forming with the adjacent part of the neck of the jar a space to receive a sealing substance to seal the joint between the plate and the jar, a cap for closing the vent, a ring rising from the plate surrounding the cap to provide a space for sealing material to seal the joint between the cap and the plate, and the cover threaded onto the upper end of the jar.

BURT E. TAYLOR.
